UNITED STATES PATENT OFFICE.

ROBERT McA. LLOYD, OF NEW YORK, N. Y., ASSIGNOR TO THE ELECTRIC BOAT COMPANY, OF NEW YORK, N. Y., A CORPORATION OF NEW JERSEY.

STORAGE BATTERY.

SPECIFICATION forming part of Letters Patent No. 684,693, dated October 15, 1901.

Application filed November 27, 1900. Serial No. 37,870. (No model.)

To all whom it may concern:

Be it known that I, ROBERT McA. LLOYD, a citizen of the United States, whose post-office address is 100 Broadway, in the borough 5 of Manhattan, in the city and State of New York, have invented certain new and useful Improvements in Storage Batteries, of which the following is a full and true description, reference being had to the accompanying 10 drawings, showing a preferred embodiment of the improvements.

The object of my invention is to provide a battery box or jar which shall be practically rigid and adapted to withstand the shocks 15 incidental to all conditions of use; and the improvement consists in the novel features of construction hereinafter described, and pointed out in the claims.

In the accompanying drawings like letters 20 refer to like parts in the several views.

Figure 1 is a perspective view of a battery-compartment with several of the new battery boxes or jars therein and with a portion of the compartment broken away to show its 25 construction. Fig. 2 is a longitudinal section of one of the preferred battery-boxes. Fig. 3 is a perspective view of the metallic crate constituting the body of the battery-box. Fig. 4 is a perspective view of the same 30 after the wooden parts have been secured thereon.

A indicates a battery-compartment for holding a plurality of my new battery boxes or jars. It is preferably made of an outer 35 box C, of iron or steel, cast in one piece or made up of sheet-metal sections and lined or coated with acid-resisting material or metal. I prefer to employ for this purpose boards coated with or saturated with acid-resisting 40 material—for instance, yellow pine thoroughly painted with asphaltum varnish—the compartment being then preferably lined with sheet-lead.

The battery-compartment made as described is exceedingly strong and light and is 45 adapted to resist the action of acids spilled or leaked from any of the battery boxes or jars B contained within the compartment, and the compartment is further adapted to 50 resist the shocks due to shifting of the boxes or jars.

To further protect the compartment from acids and from electrical leakage, the boxes or jars B rest upon wooden joists E, treated or painted with acid-resisting material, as 55 asphaltum varnish.

The form of battery box or jar which I prefer to employ is shown in detail in Figs. 2, 3, and 4 of the accompanying drawings. It is composed of a crate-like body or frame 60 (shown in Fig. 3) made up of the upright and angular corner-irons F and of the horizontal ribs or side bars G, secured to the corner-irons by rivets or other suitable devices. In order to make a tight and smooth joint 65 between the corner-irons and side bars, whereby the lead coating (added as herein-after described) is protected from being cut, the side bars are cut away or dovetailed at their ends and the corner-irons are provided 70 with a beveled edge fitting the dovetailed ends of the bars. In the spaces between the bars G are fitted wooden boards H, cut to tightly fit the spaces of the crate. The boards may be rendered waterproof and acid- 75 resisting by treating or painting with suitable material, such as asphaltum varnish, and the joints between the boards and the metallic frame may be pointed up or filled with suitable material. 80

In Fig. 4 is shown the crate with boards fitted between the bars, the whole constituting a compound box having an open bottom. This compound box is preferably lined with an acid-resisting material J, (see Fig. 2,) 85 such as sheet-lead, with the joints carefully soldered, calked, or riveted to prevent leakage of battery solution, and the whole is preferably coated with sheet-lead I or other acid-resisting material, the outer sheet being 90 folded upon the upper and lower edges of the crate to protect the same from contact of the acids.

K indicates a protecting-strip of lead applied to the upper edge of the box. 95

O indicates horizontal strips or rods of porcelain or other insulating material for supporting plate L and spacing the same from the sides of the box.

P indicates metallic shelf-supports secured 100 to the walls of the box and sustaining the insulating-strips O.

I prefer to have the bottom of the crate or box formed or composed of heavy sheet-lead Z or other light and strong acid-resisting material. When sheet-lead is used, all joints 5 therein or with the lead lining J or covering I are to be carefully soldered, riveted, or calked to prevent leakage of the solution. The box or jar made as described is preferably provided with or placed upon a support 10 or base E, for which purpose wooden boards treated in or painted with acid-resisting material—asphaltum varnish, for instance—may be employed and may be secured to the box by any suitable means, such as screws, locking-joints, hooks, soldered or molded connections, &c. This provides a base or support which in addition to being acid-resisting insulates the battery box or jar from the floor upon which it rests or from the compartment in which it is contained. 15

L indicates a battery-plate adapted to be secured by the hangers M to a supply-conductor, and N indicates one of the hard-rubber insulators between adjacent battery- 20 plates.

A battery-box of a construction substantially like that described is exceedingly strong and durable, is protected against corrosion by acids, is comparatively light in weight, 25 quite inexpensive in construction, and is adapted to withstand all the shocks and jars due to use in vessels, vehicles, or cars.

In making up the crate other forms of corner-irons and bars will readily suggest themselves and may be employed and assembled 30 differently than shown.

While I have herein shown and described one embodiment of my invention which I have found to be practical in operation, it is 35 evident that changes in and modifications of the construction herein described may be made without departing from the spirit of my invention or sacrificing its advantages, and I reserve the right to make all such alterations 40 therein as fairly come within the scope of my claims.

What I claim is—

1. A storage-battery box or jar, consisting of a metallic frame composed of a plurality of rigid metallic bars secured together in the 50 form of a crate, with a plurality of non-metallic pieces upon each side filling the spaces between the bars and secured therewith to form a practically-continuous box, and a continuous lining of acid-proof protective material 55 within the box or jar.

2. A storage-battery box or jar, consisting of a metallic frame composed of a plurality of rigid metallic bars secured together in the 60 form of a crate, with wooden boards filling the spaces between the bars and secured therewith, to form a practically-continuous box, and a practically-continuous lining of lead within the box or jar.

3. A storage-battery box or jar, consisting 65 of a tubular body comprising a frame composed of a plurality of rigid metallic bars secured together in the form of a crate, with wooden boards secured therewith to form a practically-continuous box, and a continuous 70 lining of acid-proof protective material within the tubular body, in combination with an applied acid-resisting bottom secured to the body.

4. A storage-battery box or jar, consisting 75 of a crate-like metallic body, with a plurality of non-metallic pieces upon each side secured therewith to form a practically-continuous box, and a continuous lining of acid-resisting protective material within the box or jar. 80

5. A storage-battery box or jar, consisting of a crate-like metallic body, with wooden boards secured therewith to form a practically-continuous tubular body, a continuous lining of acid-resisting protective material therefor, 85 an acid-resisting bottom secured to said body, and an insulated base or support for the box or jar.

In witness whereof I have hereunto signed my name this 22d day of November, 1900.

ROBERT MCA. LLOYD.

In presence of—

HECTOR H. HAVEMEYER,
JAMES J. COSGROVE.
